JOHN GAPP, OF SCRANTON, PENNSYLVANIA.

TRACK-SANDING DEVICE.

1,176,358.

Specification of Letters Patent. Patented Mar. 21, 1916.

Application filed June 17, 1915. Serial No. 34,569.

To all whom it may concern:

Be it known that I, JOHN GAPP, a citizen of the United States, residing at Scranton, in the county of Lackawanna and State of Pennsylvania, have invented a certain new and useful Improvement in Track-Sanding Devices, of which improvement the following is a specification.

This invention relates to track sanding devices for locomotives, and is in the nature of an improvement upon the apparatus of my prior Patent No. 1,102,577, issued July 7, 1914, the object being to provide a more simple and compact structure of the type having both a fluid pressure feed and a hand operated gravity feed, and which may be readily applied to the standard designs of locomotive sand boxes.

In the accompanying drawings: Figure 1 is a side elevation of a locomotive sand box and a portion of the boiler showing one form of my improvement applied thereto; Fig. 2, a view partially in elevation and partially in central longitudinal section of the sanding device shown in Fig. 1; Fig. 3, a transverse section taken on the line $x-x$ of Fig. 2; Fig. 4, a plan of the rotary valve; Fig. 5, a side elevation similar to Fig. 1, and showing a modified form of my improvement; Fig. 6, a view partially in section and partially in elevation, of the device shown in Fig. 5; Fig. 7, an inverted horizontal section taken on the line $y-y$ of Fig. 6; Fig. 8, a longitudinal section taken on the line $z-z$ of Fig. 9, and showing another modification; Fig. 9, an inverted plan of the device shown in Fig. 8, with a portion of the bottom plate broken away; and Fig. 10, a perspective view of one of the insert blocks used in the construction shown in Figs. 8 and 9.

According to the construction shown in Figs. 1 and 2, my improved sanding device comprises a casing, 1, preferably in the form of a single casting, having an opening at its upper end for connection with the locomotive sand box, 2. Within the casing are formed the passages, 1^a, leading to the sand receiving chamber, 3, and the gravity discharge passage, 7, leading from port, 2^a, in the valve seat to the sand delivery pipe, 8. The sand receiving chamber communicates with the gravity discharge passage by means of the upwardly curved delivery passage, 7^a. An air chamber, 4, is also formed in the

casting, to which the compressed air supply pipe, 5, is connected. This chamber serves as a separating chamber in which moisture and other foreign particles contained in the air supply may be deposited and removed at 60 convenient times by taking out the cleaning plug at the bottom of the chamber. The air then passes through an opening from the top of said chamber into the space, 6, around the spool-shaped air nozzle, 10, 65 adapted to be screwed into its position from the exterior of the casing and having a perforation, 11, in line with the sand delivery passage, 7^a, whereby the blast of air blows the sand in a continuous stream from the 70 chamber, 3, through passage, 7^a, into the sand discharge passage, 7, and delivery pipe, 8.

In the double form of sanding device, as shown in the drawings, the parts are duplicated on opposite sides of the center, one pipe, 8, leading to the front of the drivers and the other pipe leading to the rear of same, and the manually actuated valve, 9, positioned on the valve seat controls the 80 gravity discharge ports, 2^a, to either the front or rear delivery pipes. When the valve is in its middle position, both ports, 2^a, are closed, and the sanding device may then be operated by the air blast through 85 either or both of the pipes, 5, as desired. By turning the valve, 9, in one direction from its middle position, one of the ports, 2^a, is opened to discharge sand by gravity directly to the corresponding delivery pipe, 90 and when turned in the opposite direction, the other gravity port is opened to discharge sand through the other pipe. Any suitable form of mechanical connections may be employed for manually operating 95 said valve, such as the valve stem, 14, extending vertically through the casing between the discharge pipes, and provided with crank arm, 12, and rod, 13. A spring, 15, may be used for holding the valve upon 100 its seat. A removable hand hole plug, 18, affords access to the valve and its seat.

As the upward curved wall of passage, 7^a, is subject to the cutting action of the sand which may rapidly wear away the 105 same, I propose to insert at this point a removable wall section, 16, adapted to be slid into a cored recess in the casing and securely held therein by a screw plug, 17. When this section becomes worn, it may be readily 110

replaced with a new section by simply removing the screw plug, as will be readily understood.

According to the modification shown in Figs. 5 and 6, the portion containing the sand receiving chamber and the air chamber is formed as a separate section, 3^a, suitably bolted to the manifold section, 1^b, and to the section, 3^a, is attached the section, 7^b, containing the gravity discharge passage, 7, and the delivery passage, 7^a, communicating therewith, the discharge pipe, 8, being connected to the section, 7^b. In order that the section, 7^b, may be renewed separately without disturbing the other parts, the upper end is tapered to slidably engage an opening in the flange, 3^b, of section, 3^a, which is also provided with a projection, 3^d, having a recess adapted to receive the flange of the section, 7^b, the parts then being secured by the single bolt, 20. With this construction, it is a simple matter to renew the section, 7^b, by removing the bolt, 20, and detaching the pipe, 8. In this modification the rotary valve, 9, controlling the gravity discharge ports, 2^a, is operated by the bevel gears, 21 and 22, and shaft, 23, extending through the side of the casing, 1^b, and attached to the crank arm, 12, and operating rod, 13. The operation of this form of the improvement is substantially the same as before described. While the double form of sanding device is shown in the drawing, it will be obvious that a single sander may be employed wherever desired, and that in such case the parts on one side are omitted.

The modification shown in Figs. 8 and 9 is adapted for use in connection with a locomotive sand box having separate openings for delivering sand to the air jet and to the gravity discharge. In this construction the part, 2^b, indicates the flange of the sand box having openings, 1^a, communicating with the sand receiving chamber, 3, of the air jet device, and 1^c, leading to the gravity valve, 9. The casing is substantially the same as that before described, except that the gravity discharge passages, 7, and the delivery passages, 7^a, are contained in separate blocks, 7^c, inserted into large rectangular recesses in the bottom of the casing and secured therein by means of the plate, 19, bolted to the bottom of the casing. A gasket, 24, may be placed between the plate, 19, and the insert blocks for maintaining a tight joint. When the blocks become worn due to the cutting action of the sand blast, they may be readily renewed by simply removing the plate, 19, and substituting new blocks in the place of the old. As shown in Fig. 8, the air jet nozzle, 10, has the port, 11, extending longitudinally through the same and closed at the outer end by a plug, 10^a, so that in case the port should become clogged, it may be readily cleaned out by sim-

ply removing the plug, 10^a, and running a wire through the hole. This avoids the necessity of removing the jet nozzle. A cylindrical band of wire mesh, 10^b, may be placed on the spool, 10, over the port leading to the perforation, 11, for preventing the entrance of dirt into the nozzle. It will be obvious that either form of jet nozzle may be used with any one of the modified forms of sanding devices. The valve, 9, is operated to control the gravity discharge passages in the same manner as heretofore described. The bottom plate, 19, is provided with threaded openings for connection to the delivery pipes, 8, and it will be noted that in case these threaded connections become worn, it is not necessary to renew the whole casing, but merely to apply a new bottom plate. The insert blocks, 7^c, are preferably reduced at the intermediate spaces upon its sides in order to allow for easy fitting and the accumulation of fine sand dust which may readily fall out when the bottom plate is removed for cleaning.

Having now described my invention, what I claim as new and desire to secure by Letters Patent is:

1. In a track sanding device, the combination of a casing containing a sand receiving chamber, a passage for supplying sand thereto, a valve seat with said chamber, a gravity discharge passage having a separate sand supply port leading from said valve seat, a delivery passage from the said chamber to the gravity discharge passage, an air jet nozzle discharging into said delivery passage, and a rotary valve on said valve seat and controlling said gravity supply port.

2. In a track sanding device, the combination of a casing containing a sand receiving chamber, a passage for supplying sand thereto, a gravity discharge passage having a separate sand supply port, a delivery passage from the said chamber to the gravity discharge passage, a separate detachable insert for said delivery passage, and an air jet nozzle discharging into said delivery passage.

3. In a track sanding device, the combination of a casing containing a sand receiving chamber, a gravity discharge passage, a delivery passage connecting said chamber with the discharge, a separate detachable insert block for said delivery passage, and an air jet nozzle discharging into said delivery passage.

4. In a track sanding device, the combination of a casing containing a sand receiving chamber, a passage for supplying sand thereto, a valve seat within said chamber, a gravity discharge passage having a separate sand supply port leading from said valve seat, a delivery passage from the said chamber to the gravity discharge passage, an air

jet nozzle for said delivery passage, a rotary valve on said valve seat for said gravity ports, a valve stem extending through the casing, and means for actuating said valve stem.

5. In a track sanding device, the combination with a casing containing a sand receiving chamber, a gravity discharge passage, a delivery passage leading from said 10 chamber to the discharge passage, and a separate detachable block for the delivery and discharge passages and adapted to be inserted in a recess in the bottom of said casing.

15. 6. In a track sanding device, the combination with a casing containing a sand receiving chamber, a gravity discharge passage, a delivery passage leading from said chamber to the discharge passage, a removable block inserted in a recess in the bottom of said casing and containing a portion of said delivery and discharge passages, and a plate secured to the bottom of the casing 20 for holding said block in place.

25. 7. In a track sanding device, the combi-

nation with a casing containing a sand receiving chamber, a gravity discharge passage, a delivery passage leading from said chamber to the discharge passage, a removable block inserted in a recess in the bottom 30 of said casing and containing a portion of said delivery and discharge passages, and a plate secured to the bottom of the casing for holding said block in place, said plate having a threaded opening communicating 35 with the discharge passage in said block and connected to the discharge pipe.

8. In a track sanding device, the combination of a section having a sand receiving chamber and a flange provided with an opening, a detachable section having its upper end fitting said opening, and containing a gravity discharge passage and a delivery passage communicating with said sand chamber, an interlocking projection and recess between said sections, and a bolt for 40 clamping the same together. 45

In testimony whereof I have hereunto set my hand.

JOHN GAPP.
